Albert Johnson,

By Dodge and Sons,

Asso. Attorney.

UNITED STATES PATENT OFFICE.

ALBERT JOHNSON, OF LIVERPOOL, ENGLAND, ASSIGNOR TO THOMAS HENSHAW, OF LIVERPOOL, ENGLAND.

LADDER FOOT.

Application filed June 25, 1919. Serial No. 306,756.

To all whom it may concern:

Be it known that I, ALBERT JOHNSON, a subject of the King of Great Britain, residing at Liverpool, in the county of Lancaster and Kingdom of England, have invented certain new and useful Improvements in Ladder Feet, of which the following is a specification.

This invention has for its object to provide a device to be applied to ladders, scaffolding poles or the like for keeping them anchored or held more securely in position so that they cannot become accidentally displaced.

15 In the accompanying drawings:—

Figure 1 is a sectional front view of the lower end of one of the side rails of a ladder with my device applied thereto;

Figure 2 is a side elevation thereof;

20 Figure 3 is a sectional front view of the lower end of the two side rails of a ladder with my device embodying a slight modification applied thereto.

Figure 4 is a side elevation and

25 Figure 5 is a sectional view showing modifications.

In these, A is a side rail of the ladder, B the socket in which the end of a ladder side rail is held, C a clamp for holding the end of the side rail firmly against the socket, D roughnesses formed in the side of the socket so as to hold the side rail firmly, E the metallic cup shaped member to which the pad or sucker H is secured by a screw and washer G. In Figures 1 and 2 the cup shaped member is articulated to the socket by the hinge pin F, and I is a steady pin screwed through a hole in a boss J cast integral with the socket B, so that by turning this steady pin its end will impact against the cup shaped part E and steady it so as to prevent any possibility of the said cup shaped part and its pad being tripped, or in other words hold the socket and cup shaped part at a given angle relatively to one another. In Figure 3 the cup shaped parts E are made integral with the sockets B B' instead of being articulated, and K is a turn buckle screw drawing the two half sockets B B' tightly together

so as to press the roughnesses D firmly into the side rails and hold them tight. L is a hand wheel to turn the buckle screw K.

In Figure 4 the open end H' of the pad or sucker H has an angle or chamfer which bears a suitable relation to the slope of the ladder when erected in position.

In Figure 5 means are provided for regulating the distance that the respective pads or suckers H projects from the ladder end. In this the metallic cup shaped member E to which the pad H is secured, is hinged by the hinge pin F to a supplementary member L' which is provided with a screwed stem M adapted to be screwed into a screwed hole in the bottom of the socket B. By turning the members L', the respective distances that the two pads H project from the ends of the two side rails of the ladder can be varied. This is useful in cases where a ladder is erected against the building in a street having a gradient, as it enables one of the pads to project a little further from one of the side rails, than the pad projects from the other side rail, thus allowing both side rails to bear firmly on the pavement notwithstanding that the ladder is placed edge-ways on to the direction of the slope of the gradient. This avoids the use of the wedges for propping up one of the side rails at the bottom to the level of the other.

30 I declare that what I claim is:—

1. In a device of the character described, the combination of a pair of metallic members, each member having a socket formed therein for the reception of a ladder foot; a suction pad secured to the under face of each of said metallic members; and an adjustable connection between said metallic members for drawing the same together whereby the feet of a ladder may be securely held in place within said socketed members.

2. In a device of the character described, the combination of a socket member adapted to receive a ladder foot; a clamping screw thereon; a supplementary member having a screwed stem screwing into the bottom of the socket member; a cup-shaped member pivotally carried by said supplementary

member; and a cup-shaped suction pad secured to said cup-shaped member.

3. In a device of the character described, the combination of a pair of socket members each adapted for the reception of a ladder foot; a suction pad secured to the under face of each of said socket members; and an adjustable connection between said socket for drawing same together whereby the feet of

a ladder may be securely clamped in place ¹⁰ in said socket members.

In witness whereof, I have hereunto signed my name this 21st day of May, 1919, in the presence of two subscribing witnesses.

ALBERT JOHNSON.

Witnesses:

JOHN McLACHLAN,
D. M. THOMAS.
